COWL FOR OIL BURNING SMOKE SCREEN DEVICES

John Tweeddale, Torrance, Calif., assignor to The Secretary of War of the United States of America, as trustee

Application January 30, 1941, Serial No. 376,711

2 Claims. (Cl. 98—68)

This invention relates to a device adapted for use for producing a smoke screen as a defensive weapon of warfare, and more particularly to a device which may be substituted for the chemical smoke generators used by the United States Army and which are destroyed in the operation.

More particularly, it is an aim of the invention to provide an oil burning smoke screen device adapted to burn a low grade of oil which is readily available in all sections of the country and which will last for a long period of time and which may be used repeatedly to thereby materially reduce the cost of operation, and which will burn for a long period of time without attention.

It is a primary aim of the invention to provide an oil burning smoke generator the parts of which are so constructed in relation to each other that combustion of the oil in the reservoir or receptacle is reduced to a minimum, thereby permitting a full release without consumption by the burning oil of carbon particles resulting from the combustion to provide the maximum of smoke, and which despite the fact that combustion is reduced to a minimum in the generator will, due to the regulation of the air intake thereto, keep the generator burning without attention as long as any fuel remains in the reservoir or receptacle.

Still another aim of the invention is to provide by means of perfectly controlled draft regulation for consumption of the residue which offers a serious problem in most oil burning devices.

Other objects and advantages of the invention will hereinafter become more fully apparent from the following description of the drawings, which illustrate a preferred embodiment thereof, and wherein:

Figure 1 is a front elevational view of the oil burning smoke generator;

Figure 2 is an enlarged horizontal sectional view taken substantially along the plane of the line 2—2 of Figure 1;

Figure 3 is a vertical sectional view taken substantially along the plane of the line 3—3 of Figure 1;

Figure 4 is an enlarged vertical sectional view taken substantially along the plane of the line 4—4 of Figure 3;

Figure 5 is an enlarged horizontal sectional view taken substantially along the plane of the line 5—5 of Figure 3;

Figure 6 is a side elevational view showing the down draft tube detached;

Figure 7 is a cross sectional view of the same taken substantially along the plane of the line 7—7 of Figure 6.

Figure 8 is a fragmentary vertical sectional view illustrating a slight modification of the construction of the smoke generator.

Referring more particularly to the drawings, 5 wherein like reference characters designate like or corresponding parts throughout the different views, 10 designates generally the oil burning smoke generator comprising the invention and which includes a reservoir or receptacle 11 forming a pot in which oil, not shown, is adapted to be burnt and which is provided with an annular side wall 12 which flares gradually towards its upper edge so that the upper, open end of the reservoir 11 is slightly larger than its bottom. 10 A convex or dome shaped cover 13 is adapted to fit over the upper, open end of the receptacle 11 and the wall 12 thereof, adjacent its upper edge is provided with an outwardly projecting annular rib 14 on which the lower edge of the cover 13 is adapted to rest. The cover 13 at its apex is provided with an opening 15 having an annular upstanding flange 16 disposed therearound and for a purpose which will hereinafter become apparent.

15 The cover 13 is provided with an opening 17 adjacent its lower edge for receiving a down draft tube 18 which tapers from its enlarged open end 19, as best seen in Figure 6, to its restricted closed end 20. The down draft tube 18 is adapted to be inserted through the opening 17 so that its restricted end 20 will extend into the receptacle 11 and its enlarged end 19 is sized to snugly engage the opening 17 and is provided with an annular outwardly projecting flange 21 for engaging the outer side of the cover 13, around the opening 17 to form an abutment to prevent the down draft tube 18 from being passed entirely through the opening 17. As best seen in Figure 3, the down draft tube 18 is supported by the opening 17 so that it is disposed at an oblique angle to the receptacle 11 so that its closed end 20 extends to adjacent the bottom thereof. The tube 18 is provided with elongated openings 22 in opposite sides thereof and which extend substantially from end to end thereof. The upper end of the tube 18 is cut on an oblique angle relatively to its longitudinal axis so that when properly positioned in the opening 17 its flange 21 will rest flush against the outer side of the cover 13 so that the 20 diametrically opposed openings 22 will be disposed at the sides rather than at the top and bottom of the tube 18. A disk shaped plate 23 is sized to cover the open end 19 of the tube 18 to form a closure for the tube. The closure 23 is provided with an extending lip 24 which loosely

engages a pin 25 which is secured in the cover 13 for swingably mounting the closure 23 thereon relatively to the end 19 of the tube 18 to permit the closure 23 to be swung to a position for exposing the open end 19 when the oil burning smoke generator is in operation.

A stack 26 which is conical shaped is provided with a restricted end 27 which is sized to frictionally engage around the flange or collar 16 for mounting the stack 26 on the cover 13. A ring 28 is provided with an annular downwardly opening groove 29 which is adapted to receive the enlarged upper end 30 of the stack 26 for mounting the ring 28 thereon.

A pair of spaced, substantially parallel bars 31 are arranged diametrically in the ring 28 and are suitably secured at their ends to the inner side of the ring. A rod or shaft 32 is provided with a restricted portion 33, adjacent one end thereof which fits between the bars 31. Rod 32 is threaded at 34 above and below the restricted portion 33 for receiving nuts 35 for clamping the rod 32 to the bars 31.

An elbow shaped member 36 has an end 37 disposed in the ring 28 and an opposite end 38 which opens outwardly and substantially horizontally. A tube 39 is disposed in the elbow member 36 and is fastened in any suitable manner as by means of welding at 40 at one end thereof to the outer portion of the elbow member 36 so that the tube 39 extends downwardly therefrom and is positioned to engage the shaft 32 when the end 37 is in engagement with the ring 28. The shaft 32 is provided with a restricted portion 41 at its upper end for engaging an opening 42 in the outer portion of the elbow member 36. It will thus be seen that the elbow member 36 is supported by the connection of the shaft 32 and the tube 39 which is sufficiently loose to permit the end 37 to swivel in the ring 28. A pair of spaced resilient flanges 43 project upwardly from the uppermost portion of the elbow member 36, adjacent its end 38 for frictionally engaging a vane 44 which is mounted therein and which tapers away from the open end 38 and in the opposite direction thereto. A rod 45 is secured to the vane 44 and projects from the tapered or restricted end 46 thereof and is provided with a threaded free end 47 for receiving a weight 48 which is provided with a threaded bore 49 for engaging the threaded end 47 for 50 adjustably mounting the weight 48 relatively to the rod 45. It will be apparent that the weight 48 can be adjusted to correctly counterbalance the weight of the vane 44 and the end 38 so that the member 36 will be balanced above the stack 55 26 to permit the tube 39 to rotate freely on the shaft 32.

In Figure 8 a slightly modified form of construction is disclosed wherein the elbow shaped member 36' has its end 37' enlarged to fit around the outer side of the ring 28 rather than therewithin. The remaining parts of the elbow 36' correspond with the elbow 36 and it is adapted to operate in the same manner so that a further description thereof is deemed unnecessary.

Assuming that the pot 12 is filled or partially

filled with oil, not shown, the closure 23 is swung to an open position for entirely exposing the open end 19 of the down draft tube 18 after which a lighted taper or an igniting torch can be inserted into the down draft tube 18 through its open end 19 for igniting the oil in the pot 11. If desired, the smoke generator 10 may be provided with a spark igniter and wick, such as disclosed in my pending application, Serial No. 341,549, filed June 20, 1940, and entitled Smokeless oil burning orchard heaters or smoke generators. A six mile an hour wind is sufficient to turn the vane 44 and elbow member 36 to hold the end 38 away from the wind so as to produce a draft upwardly through the stack 26 to cause air to be drawn downwardly through the tube 18 and discharged laterally through its openings 32 to provide sufficiently combustion to keep the oil burning and yet to so limit the combustion that the carbon particles resulting therefrom will be released without being consumed to produce a maximum of smoke.

It has been discovered as a result of experimenting extensively with the smoke generator that the most efficient smoke output is obtained when the comparative sizes of the parts are substantially as illustrated.

Various modifications and changes are contemplated and may obviously be resorted to as only preferred embodiments of the invention have been disclosed.

I claim as my invention:

1. In a device of the character described, a stack, a ring having a downwardly opening groove for engaging the upper end of the stack, a pair of bars disposed diametrically in the ring and connected thereto, said bars being spaced laterally from each other, a rod having a restricted portion near one of its ends for slidably engaging between the rods, said end of the rod being threaded, nuts engaging the threaded end above and below the bars for adjustably clamping the rod thereto, an elbow shaped cowl having one end disposed in said ring, and a tube secured in the intermediate portion of the cowl and extending toward and disposed substantially axially of said end of the cowl, the opposite end of the rod extending into the tube and turnably engaging the same to rotatably mount the cowl above the stack and to swivelly support said end thereof within the ring.

2. For use with an oil burning smoke screen device of the character embodying a pot type burner having a downdraft air inlet, and a vertical stack associated therewith; a cowl assembly comprising an annulus having a downwardly opening groove adapted to receive the upper edge of the stack wall, an elbow shaped cowl, and supporting means rising from the annulus and upon which the cowl is mounted for rotation, the lower end of the vertical arm of the cowl and said annulus being concentrically disposed relative to one another so as to form a closed joint between said stack and said cowl which permits the rotation of said cowl.

JOHN TWEEDDALE.
